[57] CLAIM

The ornamental design for a wheelchair wheel-rim, as shown and described.

DESCRIPTION

FIG. 1 is a front elevational view of a wheelchair wheel-rim showing our new design;

FIG. 2 is a side elevational view thereof, the opposite side elevational view being a mirror image of that shown;

FIG. 3 is a top perspective view thereof; and,

FIG. 4 is a bottom perspective view thereof.

FIG. 1

FIG. 2

FIG. 3

FIG. 4
